UNITED STATES PATENT OFFICE.

WILLIAM K. HOLMES, OF BROOKLYN, NEW YORK.

LEAD-HOLDER.

1,234,666.

Specification of Letters Patent. Patented July 24, 1917.

Application filed May 7, 1917. Serial No. 166,904.

To all whom it may concern:

Be it known that I, WILLIAM K. HOLMES, a citizen of the United States, and a resident of the city of New York, borough of Brooklyn, in the county of Kings and State of New York, have invented a new and Improved Lead-Holder, of which the following is a full, clear, and exact description.

My invention relates to lead holders, and 10 has reference more particularly to means for engaging the lead in the holder to prevent the accidental displacement of same.

An object of the invention is to provide a 15 simple and inexpensive arrangement which will have a frictional engagement with the lead in the holder and prevent the lead from dropping out of the holder.

I attain the above and other objects of my 20 invention by the structure conventionally disclosed in the accompanying drawings, wherein similar characters of reference indicate corresponding parts in both views.

Figure 1 is a longitudinal fragmentary section through a lead holder embodying 25 my invention; and

Fig. 2 is a fragmentary perspective view 30 of the lead holder with the means for frictionally engaging the lead in the holder and preventing an accidental displacement of same.

Before proceeding to a more detailed description of my invention it must be clearly understood that my frictional grip has application more particularly to pencils, in 35 which the lead is backed by a feed wire and not gripped by a clutch.

Referring to the drawings, 3 is the tube which carries the lead. It has an extension 4 forming a guide for a block 5 in which a 40 bar 6 is anchored. One end of the bar enters the tube 3, against which end the lead 7 abuts when the pencil is used. The other

end of the bar 6 projects through a slot 8 in the guide 4 to engage a spiral 9 which is revoluble through the medium of a head 10 bearing in the end of a shell 11. Said shell 11 also incloses the tube 3 to which it is secured so as to prevent the rotation of said tube 3.

To prevent the dropping of the lead 7 in 50 the tube 3 I provide a notch 12 near the end of the tube 3 where the lead projects. Through this notch the surface of the lead may be frictionally engaged by a split yielding sleeve 13 which has a projection 14 entering the notch to engage the lead 7. The engagement of the depression 14 with the lead prevents an accidental displacement of the lead, but it does not interfere with the movement of the lead under the action of 60 the bar 6. The provision of the split sleeve in no way interferes with the action of the pencil, and being inclosed within the shell 11 it cannot be tampered with. The depression on the split sleeve within the notch 12 locks 65 the sleeve to the tube 3 and, therefore, prevents an accidental displacement of the split sleeve on the tube, thus the depression 14 serves two purposes,—to frictionally engage the lead within the tube and to lock the 70 sleeve on to the tube.

I claim:

In a lead holder of the class described, a tube for carrying a lead, means for moving the lead out of the tube, said tube having a 75 V-notch disposed transversely of the tube near the end where the lead is adapted to project out of the tube, and an open sleeve on the tube having a V projection entering the V notch for engaging frictionally a lead 80 located in the tube, whereby the lead in the tube is prevented from falling out.

WILLIAM K. HOLMES.
